[57] CLAIM

The ornamental design for a open seam friction rock stabilizer, as shown and described.

DESCRIPTION

FIG. 1 is a front elevational view of a open seam friction rock stabilizer showing my design;

FIG. 2 is a right side elevational view thereof;

FIG. 3 is a left side elevational view thereof;

FIG. 4 is back elevational view thereof;

FIG. 5 is a top plan view thereof;

FIG. 6 is a bottom plan view thereof; and,

FIG. 7 is a top front perspective view thereof.

FIG. 1

FIG. 2

FIG. 3

FIG. 4

FIG. 5

FIG. 6

FIG. 7
